UNITED STATES PATENT OFFICE.

WILLIAM E. KELLY, OF NEW BRUNSWICK, NEW JERSEY.

STEAM-GENERATOR.

SPECIFICATION forming part of Letters Patent No. 350,201, dated October 5, 1886.

Application filed March 31, 1886. Serial No. 197,306. (No model.)

To all whom it may concern:

Be it known that I, WILLIAM E. KELLY, of New Brunswick, in the county of Middlesex and State of New Jersey, have invented a certain new and useful Improvement in Steam-Generators, of which the following is a specification.

My improvement relates to the parts termed "headers," which are employed to connect the ends of tubes in tubular steam-generators.

My improvement has for its object to provide a novel and effective means for closing such headers.

In my improvement I employ, in conjunction with a header for closing it, a cap or cover having a bearing against the inner surface of the face or side of the header, in which is arranged the opening to be closed. The means for securing the cap or cover in place force the latter outwardly, while their thrust is sustained in rear of the cap or cover. Steam-pressure, forcing or tending to force the cap or cover outwardly, acts to tighten rather than to loosen the joint.

In the accompanying drawings, Figure 1 is a side view of the steam-generator comprising headers of the kind to which my improvement relates. Fig. 2 is a front view of a group of headers embodying my improvement and nippled together. Fig. 3 is a vertical section of headers shown in Fig. 2. Fig. 4 is a front view of a group of headers like those shown in Figs. 2 and 3, except that certain of them are cast together. Fig. 5 is a vertical section like Fig. 3, only it shows but one header, and illustrates certain modifications. Fig. 6 is a vertical section like Fig. 5, except that it illustrates certain differences of detail. Fig. 7 is a vertical section of a header such as I have shown in the similar views, Figs. 3, 5, and 6, except that it includes a different means for operating the cap or cover. Fig. 8 is a front view of a group of headers having a different arrangement of hand-holes and caps or covers. Fig. 9 is a vertical section of headers shown in Fig. 8. Fig. 10 is a front view of a group of headers severally having but two tubes connected thereto and embodying my improvement. Fig. 11 is a front view of a group of rhomboidal headers embodying my improvement. Fig. 19 is a

front view of a group of headers, which are similar to those shown in Fig. 11, except that they have differently-arranged hand-holes and caps or covers. Fig. 21 is a front view of a group of headers, which are similar to those shown in Fig. 11, except that they have different hand-holes and caps or covers. Fig. 12 is a front view of a group of rectangular headers embodying my improvement, and severally having four tubes connected to it. Fig. 13 is a vertical section of a header having a single tube connected to it and embodying my improvement. Fig. 14 is a view similar to Fig. 13, but showing certain differences of detail. Figs. 15 and 16 are views similar to Fig. 13, but illustrating differences of detail. Fig. 17 is a vertical section taken parallel to the front of a header, such as I have represented in Figs. 15 and 16. Fig. 18 is a front view of two long horizontal headers having hand-holes opposite the several tubes which are connected to the headers and embodying my improvement. Fig. 20 is a front view of a sinuous header embodying my improvement.

Similar letters of reference designate corresponding parts in all the figures.

I will first describe the steam-generator which I have shown in Fig. 1 to illustrate the use of headers embodying my improvement, premising, however, that the headers are not confined in their application to steam-generators of this style.

A designates a number of tubes, which are arranged upon an incline, and subjected to the influence of heated products of combustion from a furnace. These tubes are connected at the ends to headers B, and the headers B are united one above another and connected with a drum, C, so that water, when sufficiently heated, and steam may ascend through the inclined tubes and rise through the headers B, to which the upper ends of the inclined tubes are connected, into the drum C, and so that the cooler water will descend from the drum C into and through the headers to which the lower ends of the inclined tubes are connected, and pass from these headers into the inclined tubes. The inclined tubes are preferably secured to the headers by expanding their ends into holes in the headers.

I will now particularly describe the various

examples of headers with the appurtenances thereof which I have shown.

Referring first to Figs. 2 and 3, B designates headers, each of which is approximately triangular, but has the lower portions of the sides chamfered off vertically, the upper portions of the sides extended vertically, and a flat top. I have in this figure shown four of these headers connected together one above the other by intermediate nipples, D, which will preferably be secured in the openings d of the headers, in which they fit by expanding them into such openings. Water will flow from one header to another arranged above or below it through the connecting-nipple. Any desirable number of the headers may of course be similarly arranged and connected.

In Fig. 4 I have shown that headers, such as I have illustrated in Figs. 2 and 3, arranged one above another, may be cast integral, so as to form one structure. Any desirable number of headers may be cast together in this manner.

Each of the headers shown in Figs. 2 and 4 has three holes or openings, b' b' b', for the reception of tubes A, such as I have illustrated in Fig. 1. Each of these headers has in the front a hand-hole or opening, b⁴, of approximately triangular shape; but the corners will preferably be rounded. This opening b⁴ is closed by a cap or cover, B', which is of the same shape as the opening b⁴, only slightly larger, and is preferably provided with a rib, b⁵. This cap or cover is inserted edgewise through the opening b⁴, and then adjusted into place by the aid of handles b⁶, with which it is furnished, so that its rib b⁵ will fit the edge of the opening, and its portion which extends beyond the rib will fit against the back of that wall or side of the header in which the opening b⁴ is arranged. A packing of soft suitable material may be interposed between the edge portion of the cap and the rear surface of the front of the header.

The cap or cover B' is secured in place by means of a screw, B², whereby it is forced outward. In Fig. 3 this screw is shown as having an end bearing in the back of the header. It can rotate in this bearing. It passes through the cap or cover D', and engages with a screw-thread which is formed in the cap or cover. By engaging the cap or cover with the screw, fitting the latter in its bearing and rotating it, the cap or cover may be forced outwardly to its place. A jam-nut, E, may be applied to the screw outside the cap or cover.

I have shown in Fig. 5 that, instead of forming a screw-thread in the cap or cover, I may fit in the cap or cover an internally-screw-threaded bushing, S, for engaging with the screw. The bushing must be shaped externally so that it will not turn in the cap or cover. It will be observed that the rear portion of the screw is smaller in diameter than the forward part, where the screw-thread is located. This reduces the liability of incrustations on the screw interfering with the ad-

justment of the cap or cover. It also expedites the moving of the cap or cover to its place, because the cap or cover, when the screw is thus made, does not need to be adjusted along an unnecessary length of screw-thread.

In Fig. 6 the screw B² has a right-hand screw-thread at one end and a left-hand thread at the other. One end is inserted in a tapped hole in the back of the header, and the other end engages with a nut, G, which is fitted into the cap or cover B. This nut has a polygonal boss, to which a wrench may be fitted for the purpose of rotating it within the cap or cover, and around the screw. Thus the cap or cover will be forced outwardly. A packing may be used around the nut, if desirable. Of course I may use a second nut upon the nut G, to clamp against the outer side of the cap or cover.

Fig. 7 illustrates that a screw, B², may be made to turn loosely in the cap or cover without engaging therewith, and to screw into a tapped socket, o, in the rear wall of the header. This socket o will preferably be extended rearward, so as not to interfere with a free flow of water through the header. A jam-nut, E, may be applied to the outer end of the screw, and bear against the outer surface of the cap or cover.

Figs. 8 and 9 show that a header such as I have described may have one elliptical hand-hole, b⁷, and one circular hand-hole, b⁸, instead of a single large triangular hand-hole. The two hand-holes will have caps or covers B' of corresponding shapes combined with them. The cap or cover for the small hand-hole will be inserted through the large hand-hole. It will then be engaged with the screw B², whereby it is to be secured in place. The screw B², in this case, has a bearing in a tripod, B⁹, which bears against the rear wall of the header, and is centered by one of the tubes A. The tripod may indeed be made resilient and then can be made to hug the end of the tube so as to remain in place. It is not intended to rotate. The screw B² will be rotated after engagement with the tripod to force the cap or cover with which it engages outwardly to its place. A jam-nut, E, may be combined with the outer end of the screw. The cap or cover for the large elliptical hand-hole will be afterward inserted in the header and forced to its place by rotating a screw, B², which engages with it and has a bearing in the rear wall of the header. A jam-nut, E, is shown as applied to its outer end. This elliptical hand-hole extends opposite to two tubes A.

In Fig. 10 I have shown a group of headers severally having two tubes A connected thereto. Opposite the openings which receive these tubes there is in the front wall of each header an elliptical hand-hole b⁴. The cap or cover for such hand-hole is like the cap or cover for the elliptical hand-hole shown in Figs. 8 and 9, and is forced and held in place in like manner.

In Fig. 11 I have shown headers approximately rhomboidal in shape. Each has four

tubes A connected to it. There is a rhomboidal hand-hole, b⁴, in the front wall of each header, and this hole has a similarly-shaped cap or cover combined with it. The cap or 5 cover may be forced to its place and held there by a screw operating in any of the ways illustrated by Figs. 3, 5, 6, 7, 15, and 16. Similarly-shaped headers are shown in Fig. 19, but here 10 differently-shaped hand-holes are provided. Small circular hand-holes b⁵, like the circular hand-holes b⁸ shown in Figs. 8 and 9, are provided. They may have combined with them similarly-shaped caps or covers. An 15 elliptical hand-hole, B⁷, is also provided in each of these headers. The small circular caps or covers may be inserted through the elliptical hand-hole and secured in place by screws used like those which are shown in Figs. 8 and 9, as combined with the caps for the circular 20 hand-holes there illustrated. The caps or covers for the elliptical hand-holes b⁷ in Fig. 19 may be secured in place in the same manner as the caps or covers for the elliptical hand-holes in Figs. 8 and 9 are shown as secured 25 in place. I desire to cover, broadly, the idea of using one or more large hand-holes and a number of small hand-holes in a single header in substantially the manner described.

In Fig. 21 I have shown similarly-shaped 30 headers severally having two elliptical hand-holes extending each opposite two tubes A.

With these elliptical hand-holes, caps or covers of like shape are combined. They may be forced into place and held there in any of 35 the ways in which the caps or covers illustrated in Figs. 3, 5, 6, 7, 15, and 16 are secured in place.

In Fig. 12 I have shown a rectangular header having four tubes or pipes A secured to it. 40 It has two elliptical openings, b⁴, in the front, and to these are fitted two similarly-shaped caps or covers, B', which are secured in place in the same way as the others, as shown in Figs. 3, 5, 6, 7, 15, and 16.

In Figs. 13, 14, 15, 16, and 17 I have shown 45 a rectangular header having one or more tubes A secured to it, and provided with a single opening opposite each tube. The screw B², employed to secure the cap or cover in place, is supported at one end in a tripod in the example of my improvement shown in Figs. 13 and 14. In the example of my improvement shown in Fig. 13, the tripod bears against the back of the header, and is centered 50 by bearing against the end of the tube A, as shown in Fig. 9. The screw B² is combined with the cap or cover B', as illustrated in Figs. 2 and 9. In the example of my improvement shown in Fig. 14, the screw is rigidly connected to the tripod, and combined with a nut, G, like the screw and cover shown in Fig. 6. A 55 jam-nut, E', is shown as combined with the nut G. The screw is not intended to rotate in the example of the improvement shown in Fig. 14. The bridge-piece in this example of 60 my improvement bears against the end of the tube or pipe A, and is centered by the latter.

The headers shown in Figs. 13 and 14 severally have an elliptical opening, b⁴, and a similarly-shaped cap or cover. 70

The headers shown in Figs. 15, 16, and 17, severally, have a bar-shaped bridge-piece, P, inserted in sockets or cavities c, in the top and bottom or sides of the header. In the front of these headers, and opposite the end of each 75 tube, is an elliptical hand-hole, with which is combined a cap or cover of the same shape. The cap or cover shown in Fig. 15 is secured in place by a screw, B², which rotates loosely in the cap or cover, engaged with a tapped 80 hole in the bridge-piece. The cap or cover shown in Fig. 16 is secured in place by a screw, B², which has a bearing in the bridge-piece, but does not screw into it. This screw engages with a tapped hole in the cap or cover. 85 Outside the cap or cover a jam-nut engages with the screw and clamps it against the cover.

Fig. 18 illustrates two long horizontal headers, having elliptical hand-holes b⁴ in the front, and elliptical caps or covers, which may be 90 secured in place according to any of the ways illustrated in Figs. 3, 5, 6, 7, 9, 13, 14, 15, or 16.

Fig. 20 shows a sinuous header which may be composed of any number of sections connected by nipples D, or may be made in one piece or casting. In the front are elliptical hand-holes b⁴, having similarly-shaped caps or covers, which may be secured in place by any of the ways shown in Figs. 3, 5, 6, 7, 9, 13, 14, 100 15, or 16.

What I claim as my invention, and desire to 95 secure by Letters Patent, is—

1. The combination of a header, a cap or cover inside the same, and a securing device 105 forcing the cap or cover outwardly from the rear, substantially as specified.

2. The combination of a header, a cap or cover inside the same, and a screw having a bearing in rear of the cap or cover, and forcing the latter outwardly, substantially as specified. 110

3. The combination of a header, a cap or cover inside the same, a screw having a bearing in rear of the cap or cover, and a nut for 115 securing the cap or cover in place, substantially as specified.

4. The combination of a header, a cap or cover therefor, and a rotary screw having a bearing in rear of the cap or cover, and forcing the latter outwardly, substantially as specified. 120

5. The combination of inclined tubes, headers connected to the tubes and connected together in groups or sets beyond opposite ends 125 of the tubes, caps or covers for hand-holes in the headers, arranged inside the headers and securing devices forcing the caps or covers outwardly from the rear, substantially as specified.

WILLIAM E. KELLY.
